SEWING MACHINE

Norman V. Christensen, Chicago, Ill., assignor
to Union Special Machine Company, Chicago,
Ill., a corporation of Illinois

Application June 8, 1935, Serial No. 25,590

1 Claim. (Cl. 112—220)

This invention relates to sewing machines, and particularly to sewing machines of the rotary hook type.

In sewing machines of the rotary hook type, a rotating ratio of 2:1 is usually provided between rotary hook and feed operating shafts disposed beneath the work plate of the machine. This is because the feed must operate with every stroke of the needle, while the rotary hook must rotate two or more times for every such stroke. It is an object of my invention to provide simple, compact, and reliable, drive means between the feed shaft and rotary hook shaft to produce this ratio, the drive means being of such character as to permit operation of the machine at much higher speeds than ordinarily, with attendant lessening of noise and vibration, and to simplify materially the matter of lubrication of rotating parts.

Heretofore it has been proposed to house the mechanism for transmitting power from the main shaft to the feed shaft of a sewing machine within a closed standard, and thus to seal these parts effectively for the purpose of lubrication, and to employ additionally a separate sealed casing for housing a gear transmission between the feed shaft and rotary hook shaft. An important advantage of the present invention is that it dispenses with the necessity for employing such a separate casing for housing a gear transmission between the feed shaft and rotary hook shaft, with the result that all of the power transmitting mechanism requiring lubrication is confined to the interior of the hollow standard.

As an example of my invention, I have shown a sewing machine in which a transmission shaft beneath the work plate of the machine for actuating the feed element rotates in unison with the main shaft by which the needle is operated; and from this feed shaft rotation is imparted to a countershaft upon which the rotary hook is mounted. The invention is also applicable to a reverse arrangement in which the transmission shaft is driven at a higher rate of speed, with the rotary hook mounted thereon and the proper reduced rate of rotation imparted to a countershaft by which the feed is operated.

Other objects and advantages of my invention will be manifest from the following description, having reference to the accompanying drawings, whereof:

Fig. I is a view partly in side elevation and partly in vertical section, of a sewing machine embodying the present improvements.

Fig. II is a transverse section, taken as indicated by the arrows II—II in Figs. I and III; and

Fig. III is a fragmentary staggered plan sectional view, taken as indicated by the arrows III—III in Fig. I.

In these illustrations, the numeral 1 designates the work support of the machine from which rises, at one end, a hollow standard 2 with an integral tubular horizontal arm 3 over-reaching said work support. Suitably journaled within the hollow arm 3 is the main drive shaft 4 of the machine, said drive shaft being fitted at the rear end with a hand wheel 5, and a pulley 6 adapted to be connected by belt with a motor or other source of power. Vertically reciprocating in a head 7 at the end of the overhanging arm 3 is a needle bar 8 which carries a seaming needle 9, and which, through suitable connections (not illustrated) is actuated from the main drive shaft 4. At 10 there is shown a take-up member for the needle thread (not illustrated), which member may also be actuated in a well-known manner through suitable connections with the main shaft 4. The head 7, moreover, affords vertical guidance to a presser bar 11 which, at its lower end, carries a presser foot 12 of ordinary construction.

Extending longitudinally of the machine below the work support 1 is a transmission shaft 13, 30 which, at its front end, is journaled in a bushing 14 secured in a pendant bearing lug 15 of the work support 1. The rear end of the transmission shaft 13 extends through a bearing bushing 16 into an oil well 17. Secured to said shaft within the chamber 17 is a spur gear 18, 35 preferably formed from non-resonant material such as bakelite, and provided with a metallic hub. The wheel 18 constitutes one element of a gear train which includes idler gears 19, 20, 40 and a drive gear 21 secured to the main shaft 4. The gears 19 and 21 may be wholly of metal, while the gear 20, like the gear 18 is preferably made from bakelite and provided with a metallic hub. The gear wheels 19, 20 are supported 45 for free rotation between collars 22, 23, respectively on pins 24, 25 suitably secured against rotation in opposite side walls of the hollow standard 2 which houses the gear train. As shown, the gear wheel 18 dips into the oil within the well 17, and, in rapid rotation, splashes the gear wheels 18, 20 and 21. The splash lubricant falling upon the gears 19, 20 finds its way through apertures 26, 27 in the collars 22, 23 to spiral oil distributing grooves 28, 29 internally 50 55

of the hubs 30, 31 of said gears. The ratio of the train gears, in this instance, is such that the transmission shaft 13 is driven in unison with the main driving shaft.

Secured to the transmission shaft 13 (Fig. III) adjacent the bearing 15, is a rotary member 32, which, through an arm 33 on a rock shaft 34 journaled in fixed lugs 35 on the work support 1, actuates the feed element 36 of the machine. By virtue of the described arrangement, the feed element 36 is actuated once for each reciprocation of the needle bar 8.

Also journaled in a pendant bearing 37 of the work support 1 is a countershaft 38 which parallels the transmission shaft 13, and which, at its front end, carries a rotary hook 39 to cooperate with the seaming needle 8. To the inner end of the rotary hook shaft 38 is secured a small toothed wheel 40 which is coordinated by an endless flexible belt 41 of leather, woven fabric, or the like, having equi-spaced projections 41a, with a larger toothed wheel 42 fast on the transmission shaft 13. The diametral ratios of the toothed wheels 40, 42 is one to two so that the rotary hook shaft 38 is driven at twice the speed of said transmission shaft 13, and it therefore makes two revolutions during each actuation of the needle 8 and the feed element 36, as required. If desired or found convenient in practice, a "silent" sprocket chain may be substituted for the belt 41.

As an alternative, the wheels of the gear train 18-21 may be proportioned to drive the transmission shaft 13 at twice the speed of the needle 8 actuating or main shaft 4, and the rotary hook 39 mounted directly on said transmission shaft. Under these circumstances, the rotary actuating member 32 for the feed element 36 is mounted on a countershaft, and the position of the toothed wheels 40, 42 reversed to determine rotation of said countershaft at half the speed of the transmission shaft for actuation of the feed element in unison with the needle 8 as before.

According to the preferred practice of my invention, the projections 41a on the belt 41 are of such number, with relation to the notches of the wheels 40, 42, that the wear between these

elements is evenly distributed. More specifically, this is accomplished by having the ratio between the number of cross bars 41a and the number of notches on the wheels 40, 42 constitute a repeating fraction whereby each cross bar will not always enter into the same notch of either wheel which it has previously entered in its passage around that wheel.

Desirably the belt 41 is made of non-stretchable fabric and is sufficiently taut to prevent any lost motion between the feed shaft 13 and the rotary hook shaft 38. The close proximity of these shafts is a further factor in insuring the maintenance of the proper timed relation between the shafts.

It will be noted that the use of the flexible drive of this invention eliminates the necessity of employing an additional casing to house the transmission between the feed shaft and rotary shaft, for the flexible belt requires no lubrication and may be exposed beneath the work support.

From the foregoing, it will be seen that, in addition to being simple and efficient, the transmission of my invention is advantageous because it favors noiseless and vibrationless operation of the sewing machine at high speeds, simplifies materially the matter of lubrication, and at the same time insures proper timed relation between the feed shaft and rotary hook shaft.

Having thus described my invention, I claim:

In a sewing machine, a work support with an overhanging arm; a needle; a rotary needle-actuating shaft supported by said arm; a needle actuated from said shaft; feeding means with an actuating shaft therefor also beneath the work support; a rotary hook and a shaft therefor beneath the work support; and means whereby the feed-actuating and the rotary hook shafts are driven in the same direction but oppositely to the needle actuating shaft, including a belt connecting sprockets respectively on said rotary hook and feed-actuating shafts, spur gears respectively on the needle and the feed actuating shafts, and a plurality of interposed intermeshing idler gears connecting said spur gears.

NORMAN V. CHRISTENSEN.
